US00D616879S

(12) **United States Design Patent**
Kim et al.

(10) **Patent No.:** **US D616,879 S**
(45) **Date of Patent:** ** Jun. 1, 2010

(54) **MOBILE PHONE COVER**

(75) Inventors: **Yun-Su Kim**, Seoul (KR); **Sang-Min Hyun**, Seoul (KR); **Seog-Guen Kim**, Seoul (KR)

(73) Assignee: **Samsung Electronics Co., Ltd.**, Suwon-Si (KR)

(**) Term: **14 Years**

(21) Appl. No.: **29/340,918**

(22) Filed: **Jul. 28, 2009**

(30) **Foreign Application Priority Data**

Apr. 8, 2009 (KR) 30-2009-0014752

(51) **LOC (9) Cl.** **14-03**

(52) **U.S. Cl.** **D14/250**; D14/248

(58) **Field of Classification Search** ..... D14/138 AA, D14/138 AD, 138 G, 140, 142, 167, 217, D14/218, 240, 242, 248, 250–253, 299, 341–347, D14/440, 203.1–203.8; D3/200–201, 218–219, D3/228, 269, 301, 273; D13/103, 107–108, D13/119; 220/4.02; 224/191, 240, 241, 224/245, 682–683; 248/206.2–206.4, 220.21, 248/279.1, 309.1; 361/679.3, 679.56; 379/420.04, 379/426, 433.11, 446–447, 454, 455; 455/575.1, 455/575.6, 575.7, 575.8, 575.9; 190/100; 206/305, 320

See application file for complete search history.
